UNITED STATES PATENT OFFICE.

CHARLES GLOVER, OF NEW BRITAIN, CONNECTICUT.

PLATING-MACHINE.

No. 892,417.

Specification of Letters Patent.

Patented July 7, 1908.

Application filed October 22, 1907. Serial No. 398,594.

To all whom it may concern:

Be it known that I, CHARLES GLOVER, a citizen of the United States, residing at New Britain, county of Hartford, State of Connecticut, have invented certain new and useful Improvements in Plating-Machines, of which the following is a full, clear, and exact description.

My invention relates to improvements in plating machines.

The objects of my invention are—to provide an improved construction for plating machines, including improvements in a carrier adapted to move certain conveyers through the plating solution, which conveyers may be readily detached at will for the substitution of new articles to be plated.

The particular advantages will be appreciated by a reading of the following description.

In the drawings—Figure 1 is a view in end elevation of the machine with the tank in section; Fig. 2 is a view in side elevation with the tank and bearings in section; Fig. 3 is a plan view of the plating machine; Fig. 4 is an enlarged detail view partly in section, and partly broken away; Fig. 5 is a transverse sectional view of Fig. 4; Figs. 6 and 7 are enlarged detail views of the opposite sides of one end of the conveyer frame.

1 is a tank adapted to contain the plating solution.

2 is a shaft mounted to rotate in the bearings 3, secured in the ends of the tank.

35 4 is a stuffing-box through which an extension of the shaft 2 passes. 5 is a pulley-wheel secured to the said extension on the exterior of the tank.

6—6^a are the ends of the carrier frame, the same being secured to the shaft 2.

7 is a container for articles to be plated. 8 is a supporting rod therefor. This rod may carry the articles directly or indirectly, as where the container 7 is used. In the latter case, the rod 8 passes through the container at the centers of the ends 9—9. One or both of the ends 9 may be removable, or one may be fixed in the end of the container 7 and secured to the rod 8 as by key 8^a, or if both ends are removable the container may be fastened to the rod 18 by a removable pin connection 7^a and the key 8^a. (Fig. 4.)

10—10 are clips or buttons on the carrier frame 6—6^a, adapted to detachably engage the rod 8 and secure the same to the respective frames.

11 is a handle projecting from each end of the container 7.

12 is a rheostat connected to the positive terminal of the source of electricity.

13 is an insulated connection between the rheostat 12 and a contact 15 on the bearing 3.

14 is a reduced extension of the shaft 2. This extension 14 is mounted in the bearing 3 and makes electrical connection with the contact 15.

The carrier frame 6^a may be formed in two sections. 16—16 indicate a series of arms, radiating from and in contact with extension 14, on one section of 6^a, said arms being adapted to form a contact with the rods 8 when the same are secured in place. 16^a is a ring secured in the opposite section of 6^a and bears against the arms 16—16, when the two sections are secured together.

17 indicates a series of metallic strips or rods, rotatably secured at one end to the rods 8.

18—18 are sleeve-like spacers placed between the members 17 on rod 8.

19—19 indicate negative poles suspended in the plating solution and connected together in any well-known manner.

20 is a connection leading from the poles 19 to the negative pole of the source of electricity.

The main body of the shaft 2 is preferably made of wood, or some non-conducting material, and the same is true of the frame ends 6—6^a. The shaft extension passing through the stuffing-box 4 and the extension 14 are preferably made of metal, and are electrically disconnected at all times. It follows, therefore, that electricity entering through the wiring 13 can proceed onwardly only by passing through the extension 14, arm 16, rods 8, the articles carried thereby, and thence through the solution to the negative terminals 19. By this arrangement no chance of leakage of electricity is afforded.

The cylindrical parts of the container 7 are preferably formed of celluloid, or some other efficient non-conducting material of sufficient strength for practical use in this construction, and preferably attached to one of the ends 9 which is secured against rotation.

The operation is as follows: The proper plating solution and anode terminals 19 are employed and put in place. The articles to be plated are then electrically connected with the rod 8. In case small articles are to be

plated, which cannot be conveniently secured to the rods 8, they are placed in the perforated barrels 7—7 and are kept in circuit through the medium of the rods 17, the 5 rods and small articles assuming the same position in the barrel by gravity. Other articles which, for example, are perforated, may be placed directly upon the rods 8, for instance, such as shown in the lower part of 10 Fig. 2. These rods are detachably secured to the rotating frame through the medium of the clips or buttons 10 on the ends 6—6^a. The plating of the articles, whatever they 15 may be, occurs in the usual manner and requires no detailed description. The carrier frame within the solution rotates at comparatively slow speed, for example, five or six revolutions per minute, although the speed is immaterial. When rotating at a 20 comparatively slow speed, the operator in charge of the plating machine may easily and quickly remove any one of the rods 8 and the devices carried thereby and substitute another one. For convenience in removing 25 the barrels, handles 11 are employed, although of course their presence is not absolutely essential.

The plating solution is preferably of such a depth as to always cover the articles to be 30 plated when they are in proper position to receive the same.

What I claim is,

1. In a plating machine, a tank, a rotatable frame therein, a series of independent 35 means each comprising an electrode carried by said frame and each adapted to support one or more articles to be plated.

2. In a plating machine, a tank, a rotatable shaft, spaced-apart frames on said shaft, 40 means comprising an electrode connected with said spaced-apart frames for supporting one or more articles to be plated.

3. In a plating machine, a tank, a rotatable shaft, spaced-apart frames on said shaft, 45 removable means comprising an electrode connected with said spaced-apart frames for supporting one or more articles to be plated.

4. In a plating machine, a tank, a rotatable shaft, spaced-apart frames on said shaft, 50 removable means comprising an electrode and container connected with said spaced-apart frames for supporting the articles to be plated.

5. In a plating machine, a tank, a rotatable frame, a series of rods carried by said frame and adapted to support one or more articles to be plated, a source of electricity, and connections established through said 55 rotatable frame and rods.

6. In a plating machine, a tank, a rotatable frame, and a series of independent containers each comprising an electrode carried 60 by said frame.

7. In a plating machine, a tank, a rotatable frame, and a series of independently removable containers each comprising an electrode carried by said frame. 65

8. In a plating machine, a tank, a rotatable frame, a series of perforated tubular members, a removable closure in the end of each of said members, and means to secure the same to said frame. 70

9. In a plating machine, a tank, a rotatable shaft, spaced-apart frames thereon, a series of removable rods connected with said frames, a source of electricity, electrical connections established through said shaft, frame and the rod, and a tubular container having a removable closure end adapted to be mounted on said rods. 75

10. In a plating machine, a tank, a rotatable frame, a series of independent supports carried thereby, and a cylindrical container comprising an electrode carried by one of said supports. 80

11. In a plating machine, a tank, a rotatable frame, a tubular container, and a removable closure in the end of said container. 85

12. In a plating machine, a tank, a rotatable frame, a container detachably supported 90 thereby, and a removable closure for said container.

13. In a plating machine, a tank, a rotatable frame, a perforated container detachably supported thereby, and a removable end 95 closure for said container.

14. In a plating machine, a tank, a rotatable frame, a detachable supporting rod carried by said frame, a cylindrical container, and removable means supporting said container on said rod. 100

15. In a plating machine, a tank, a non-metallic shaft, bearings therefor, supporting frames on said shaft, a supporting rod connected to said frames, a metallic shaft extension at one end of said shaft, an electrical connection in one of said bearings in contact with said shaft extension, and an electrical connection from said extension to said supporting rod. 105

16. In a plating machine, a tank, a non-metallic shaft, bearings therefor, metallic extensions carried by said shaft insulated from each other and extending into said bearings, supporting frames on said shaft, metallic work supporting rods connected with said frames, an electrical connection through one of said frames from one of said shaft extensions to said metallic work supporting rods, and an electrical contact for 115 the last mentioned shaft extensions, said contact being adjacent to the bearing therefor. 120
